UNITED STATES PATENT OFFICE.

GEORGE W. CASSIDY, OF NEW YORK, N. Y.

DESIGN FOR A COMBINED BOWL AND DIFFUSING-SHADE.

52,521.

Specification for Design.

Patented Oct. 8, 1918.

Application filed March 15, 1918. Serial No. 222,740. Term of patent 7 years.

To all whom it may concern:

Be it known that I, GEORGE W. CASSIDY, a citizen of the United States, and a resident of the borough and county of Queens, city and State of New York, have invented a new, original, and ornamental Design for a Combined Bowl and Diffusing-Shade, of which the following is a specification, reference being had to the accompanying drawing, forming part hereof.

The said drawing is an elevational view of a combined bowl and diffusing shade, showing my new design.

I claim:

The ornamental design for a combined bowl and diffusing-shade as shown.

In witness whereof I have hereunto signed my name this eighth day of March, 1918.

GEORGE W. CASSIDY.
